UNITED STATES PATENT OFFICE.

JULIA E. MEYENBERG, OF CHICAGO, ILLINOIS.

CEILING-SUPPORTER.

SPECIFICATION forming part of Letters Patent No. 533,659, dated February 5, 1895.

Application filed April 28, 1894. Serial No. 509,351. (No model.)

To all whom it may concern:

Be it known that I, JULIA E. MEYENBERG, a citizen of the United States, residing at Chicago, in the county of Cook and State of Illinois, have invented a new and useful Ceiling-Supporter, of which the following is a specification.

This invention relates to ceiling supporters for the support of fire-proof ceiling materials.

10 To this end the main and primary object of the present invention is to construct a cheap, simple, and efficient device of this character to be used in connection with the ordinary wooden floor-beams or joists, whereby it may be rendered practicable to build floors and 15 ceilings with wooden beams or joists, and to secure to the under side of the floor beams or joists suitable fire-proof material, thereby obtaining perfect protection against fire that 20 would otherwise destroy the beams or joists.

With these and other objects in view which will readily appear as the nature of the invention is better understood, the same consists in the novel construction, combination 25 and arrangement of parts hereinafter more fully described, illustrated and claimed.

In the accompanying drawings:—Figure 1 is a sectional perspective view of a fire-proof ceiling supported in position from wooden 30 floor-beams or joists by the herein described ceiling supporting plates. Fig. 2 is a detail in perspective of one of the plates. Fig. 3 is a detail plan view of the blank of metal from which the plates are stamped and pressed.

35 Referring to the accompanying drawings, 1—1 designate ordinary wooden floor beams or joists that are arranged parallel with each other and at regular distances apart, the same being used in the construction of ordinary 40 floors and ceilings, and in the present invention a series of ceiling supporting plates 2, are adapted to be secured to both sides of each joist at the lower edges thereof to provide means for supporting in position the 45 ordinary ceiling tiles or slabs 3, that are usually employed to form fire-proof ceilings.

The ceiling supporting plates 2, are stamped from a single blank of iron or other suitable strength metal and of a size sufficient to suit 50 the load or weight that is to be supported thereby.

The ceiling supporting plates 2, are provided with a vertical portion, having near its upper end a series of screw or nail holes 4 adapted to receive suitable nails or screws 55 for fastening the plates to the floor beam or joists, and at the lower end of said plates the same are provided with the right-angularly disposed main supporting flanges 5. The main supporting flange 5, is disposed outward from the beam or joist to which the supporting plate is attached, and is adapted to receive thereon one side edge of the ceiling tiles or slabs that are arranged between the floor beams or joists to span and fill up 60 the space there-between, and said main supporting flange 5, may also be provided with the screw or nail holes 6, to receive suitable screws or nails for more securely connecting the tiles or slabs therewith, and thereby additionally strengthening the entire ceiling construction.

The ceiling supporting plates 2, are further provided in the vertical body portions, thereof, with the openings 7, from the upper and lower 75 ends of which are bent outwardly the upper and lower flanges 8 and 9 respectively, the lower flange 9, of which is disposed in a line with the flange 5, but is projected at right angles to the plate from the opposite side 80 thereof so as to be disposed directly under the floor beam or joist to which the plate is attached. The upper of said flanges 8, is disposed parallel with the flange 9, and projects outwardly from the same side of the plate, 85 but is adapted to take under the floor beam or joists and to rest directly against the under side thereof, and therefore acts in the capacity of a level-flange to engage against the under side of the floor beam or joist and 90 thereby always secure the proper positioning of the attachment plates, so that the main and auxiliary supporting flanges 5 and 9 respectively will be precisely leveled to support the ceiling tiles or slabs. The flanges 8 and 9, of the supporting plates are also provided with the screw or nail holes 10, to receive screws or nails or other suitable driven fasteners, the upper flange 8, being secured to the upper side of the floor beam or joist, 100 and the lower flange 9, being adapted to support thereon one edge of the supplemental

beam or joist tiling, 11, or other similar material that is adapted to be placed directly under the beam or joist, so as to fill in the space left between the parallel rows of ceiling supporting plates secured to both sides of the beams or joists.

- In arranging the ceiling supporting plates they are preferably arranged in pairs as illustrated in Fig. 1, of the drawings, the plates of each pair being secured to directly opposite sides of each floor beam or joist so as to dispose the inner flanges 8 and 9 under the beam or joist to confine there-between the supplemental tiling 11, and to dispose the main horizontal flanges 5 outwardly to receive one edge or end of the main tiles or slabs 3, thereby completing a simple and efficient construction for the perfect and practicable support of a fire-proof ceiling.
- In making the supporters, the same are stamped out of a single blank of metal as illustrated in Fig. 3 of the drawings, and the several flanges are pressed into shape by means of any suitable press, and it will be understood that changes in the form, proportion and the minor details of construction may be resorted to without departing from

the principle or sacrificing any of the advantages of this invention.

Having thus described the invention, what is claimed, and desired to be secured by Letters Patent, is—

1. The herein-described ceiling supporting plate provided with tile or slab supporting flanges at its lower end, and an intermediate leveling flange adapted to engage under a floor beam or joist, substantially as set forth.
2. The herein-described ceiling supporting plate made from a single blank of metal and provided at its lower end with opposite right-angledly disposed tile or slab supporting flanges projecting from opposite sides, and an intermediate leveling flange adapted to engage directly under a floor beam or joist, all of said flanges being provided with screw or nail holes, substantially as set forth.

In testimony that I claim the foregoing as my own I have hereto affixed my signature in the presence of two witnesses.

JULIA E. MEYENBERG.
